UNITED STATES PATENT OFFICE.

FREDERICK W. ROBERTSHAW, OF PITTSBURGH, PENNSYLVANIA.

FLUSHING-VALVE FOR CLOSET-TANKS.

1,292,518.

Specification of Letters Patent. Patented Jan. 28, 1919.

Application filed April 18, 1917. Serial No. 162,827.

To all whom it may concern:

Be it known that I, FREDERICK W. ROBERTSHAW, a citizen of the United States, residing at Pittsburgh, Allegheny county, Pennsylvania, have invented a new and useful Flushing-Valve for Closet-Tanks, of which the following is a full, clear, and exact description, reference being had to the accompanying drawings, forming part of this specification, in which—

Figure 1 is a sectional elevation, partly broken away, illustrating my invention.

Fig. 2 is an end view.

Fig. 3 is a view partly in side elevation, and partly in vertical section.

Fig. 4 is an elevation of a part of the device looking at the opposite side from Fig. 3, and

Figs. 5 and 6 are sectional detail views.

My invention has relation to flushing valves for closet tanks, and is designed to provide a simple and efficient valve apparatus of this character which can be manufactured at a relatively low cost and which will be effective in service.

A more particular object of my invention is to provide a device of this character in which the parts are so arranged that the controlling float rests upon the surface of the water in the tank, instead of being submerged therein. Heretofore in all float controlled devices of this character with which I am familiar, it has been necessary to set the float at such a low level in the tank that it is entirely submerged when the tank is filled.

It has been found that submerged floats, no matter how carefully they may be constructed, soon become water-logged in use, and fail to operate properly. My invention

provides an arrangement of such character that the parts may be set at any desired level and at the same time hold the valve open sufficiently long to empty the tank.

Another object of my invention is to provide an improved trip device for holding the valve open and for releasing it when the tank is emptied.

A still further object is to improve the construction and character of the valve itself whereby a close and effective seating is at all times insured, and leakage is prevented.

Other objects of my invention will hereinafter appear.

Referring to the accompanying drawings, in which I have shown the preferred form of my invention, and which will now be de-

scribed, the numeral 2 indicates a closet tank of any usual or suitable character and which in service is provided with any usual or suitable water inlet valve. This inlet valve 60 forms no part of my present invention, and hence is not illustrated. 3 designates the flush outlet for the tank, which is in the form of a hollow sleeve plug seated in an opening in the bottom of the tank and secured by the nut 4, or in any other usual manner. The upper portion of this plug has a lateral communication at 5 with the lower end of the usual vertical overflow pipe 6.

The upper end of the plug 3 forms a valve 70 seat which is preferably flared outwardly, as indicated at 7. 8 designates my improved valve, which preferably consists of a flexible disk of rubber seated against a flange 9 on the lower section 10 of the valve stem, the 75 flange 9 being of considerably less diameter than that of the disk. In order to avoid any possibility of this flange working loose, it is preferably either rigidly secured to the stem member 10, or cast integrally therewith, as shown in Fig. 3. 11 is a washer which is seated against the central upper face of the valve disk, this washer being also of less diameter than the disk. It is clamped in place by a nut 12, which is threaded onto 80 the upwardly projecting threaded portion 13 of the stem member 10. This projection is made hollow and is interiorly threaded to receive the lower threaded end portion of the stem member 14. The stem member 14 90 has a threaded engagement at its upper end with the internally threaded sleeve portion of a head member 15. This head member has a squared portion 16 which slides in a guide opening of a laterally projecting arm 95 17, which is adjustably secured to the overflow pipe 6 in any suitable manner, as by a set screw 18. The lower stem member 10 has a sliding guide bearing at 19 in the plug 3. 20 is a nut on the threaded upper portion of the stem member 14 and which is adapted to screw upwardly against the lower end of the head 15. Preferably the socket in the sleeve portion of said member is provided with a lateral opening 21 at its upper 105 portion so as to permit the escape of any dirt, etc., from the interior thereof.

22 designates a float which is secured at the end portion of a float arm 23. This float arm is secured at its inner end in a projection 24 of an arm 25 which is pivoted to the arm 17 at the point 26. The arm 25 has at

its upper end a cam-shaped shoe 27 whose upper surface is eccentric with respect to the center 26. 28 is a dog which is pivoted at 29 in the bifurcated upper end portion of the head 15. This dog has the depending weighted arm 30 and the projecting point or pawl portion 31, at the opposite side of the pivot 29. The dog is normally held in the position shown in Fig. 6 by the weight 30 resting against the sleeve portion of the head 15. A stop pin 31^a prevents the dog from being swung outwardly beyond a predetermined position. 32 designates a lift or pull device of any suitable character which is loosely engaged with the stem member 14 and which by its engagement with the nut 20 provides means for raising the stem and valve to the position shown in Fig. 3.

The operation is as follows: The arm 17 is adjusted on the overflow pipe 6 at about 20 the desired water level in the tank, so that when the tank is filled to this normal level the float is resting on the surface portion of the water, as shown in Fig. 1. In this manner the float is kept from being submerged, and the operating parts of the trip are above the water level. When it is desired to empty the tank, the lift device 32 is actuated, thereby raising the valve to a position slightly 25 above that shown in Fig. 3. As soon as the lifting device 32 is released the valve and its stem drops until the point 31 of the dog 28 comes into engagement with the upper curved surface of the cam shoe 27. This 30 holds the valve open and permits the continued outflow of the water from the tank. As the tank empties, the float gradually falls, the curved surface 27 of the cam shoe riding under the point of the dog 28 until 35 it drops off the right hand end (looking at Fig. 3) of said shoe. The valve then seats by gravity. The tank then begins to refill 40 and raises the float to its normal position.

The eccentricity of the curved surface 27 45 of the cam shoe performs two functions. First, it overcomes any tendency of the dog to stick on said surface, by providing a sharper curvature or inclination of that portion of such surface upon which it rests while 50 the tank is emptying. Second, it results in a lowering movement of the valve and its stem while the tank is emptying, so that at the time the valve is released it has a less distance to drop to its seat.

55 It will be noted that the cam surface 27 is sufficiently elongated so that the tank has time to empty before the valve is released. It is this feature which enables me to place these parts at a sufficient elevation to keep 60 the float from being submerged. It will be further seen that by reason of the elongation of this cam surface a great variation is possible in the height at which the parts are set in the tank. This gives a wide range of 65 adjustment, so that the device can be readily

adapted to different conditions and varying depths of tanks.

The construction of the valve itself, in the feature of having the flexible valve disk of considerably larger diameter than its support and washer, is an important one. This construction enables the central and rim or seating portions of the valve to flex with respect to each other. As the valve comes to its seat the pressure of the water above the 70 valve, as well as any suction which may exist in the outlet connection 4, draws the valve closely to its seat, giving it the cupped form shown in dotted lines in Fig. 1. This movement of the seating portion of the flexible valve disk also gives it a wiping action upon the seating edge of the outlet connection, keeping the latter free from dirt, and insuring a tight seating of the valve disk at 75 all times.

80 The central stem section 14, having threaded engagements at its end portions with the sections 10 and 15 can be readily adjusted to various lengths, according to the height at 85 which the arm 17 is adjusted on the pipe 6 in any particular case.

The entire device is extremely simple in 90 its construction, character, and mode of operation; and can be manufactured at a relatively low cost, as very little machine work 95 is required. The device can also be quickly and readily installed in the tank. All the parts are readily accessible and detachable in case repairs are necessary.

I do not desire to limit myself to the particular construction and arrangement of the parts which I have herein shown and described, since it is obvious that various changes may be made in the details of these parts without departing from the spirit and 100 scope of my invention as defined in the appended claims.

I claim:

1. A flushing valve for closet tanks, comprising a valve proper having an upwardly 110 extending stem, a dog pivoted to said stem above the water level of the tank, a support for said dog to hold the valve in unseated position, said support having an elongated supporting surface, and a float for controlling the said support, substantially as described.

2. A flushing valve for closet tanks, comprising a valve proper having an upwardly 115 extending stem, a dog pivoted to said stem above the water level of the tank, a support for said dog to hold the valve in unseated position, said support having an elongated supporting surface, and a float for controlling the said support, said float having its 120 major portion at all times above the water level of the tank, substantially as described.

3. A flushing valve for closet tanks comprising a valve proper having an upwardly 125 extending stem, a dog pivoted to said stem, 130

a support for engagement with the dog to hold the valve in unseated position, said support having an elongated curved supporting surface, and a float controlling the position 5 of said support, substantially as described.

4. A flushing valve arrangement for closet tanks, comprising a valve proper having an upwardly extending stem, a dog pivoted to said stem, a supporting member for engagement with the dog to hold the valve unseated, said dog being arranged to pass upwardly above the said support on the upward movement of the valve stem but to engage the support to hold the valve unseated, 10 and a float operatively connected to the support and acting to move the support out of engagement with the dog as the water level in the tank falls, the support having an elongated supporting surface, substantially 15 as described.

5. A flushing valve arrangement for closet tanks, comprising a valve having an upwardly projecting stem, a dog pivoted to said stem, an overflow pipe, a support adjustably mounted on said pipe, a float lever 20 pivoted to said support, a shoe connected to said float-lever to be rocked thereby, said shoe

having a supporting surface for engagement with the dog when the valve is unseated, the said dog having a nose portion which will 30 ride past the shoe when the valve and stem are raised, but will engage the shoe to hold the valve unseated, the dog also having a depending weight arm, substantially as described.

6. A flushing valve arrangement for closet tanks, comprising a valve having an upwardly projecting stem, a dog pivoted to said stem, an overflow pipe, a support adjustably mounted on said pipe, a float lever 40 pivoted to said support, a shoe connected to said float-lever to be rocked thereby, said shoe having a supporting surface for engagement with the dog when the valve is unseated, said supporting surface being 45 curved and the curve being eccentric with respect to the pivotal center of the float, substantially as described.

In testimony whereof I have hereunto set my hand.
